CROCHET FRAME

Katie L. Cox, Atlanta, Ga.

Application May 13, 1949, Serial No. 2,643

Term of patent 14 years

(Cl. D47—5)

To all whom it may concern:

Be it known that I, Katie L. Cox, a citizen of the United States of America, residing at Atlanta, in the county of DeKalb and State of Georgia, have invented a new, original, and ornamental Design for a Crochet Frame, of which the following is a specification, reference being had to the accompanying drawing, forming part thereof, and wherein:

Fig. 1 is a plan view of a crochet frame, embodying my invention.

Fig. 2 is a side view of the crochet frame shown in Fig. 1.

Fig. 3 is a top end view of the crochet frame shown in Fig. 1.

Fig. 4 is a bottom end view of the crochet frame shown in Fig. 1.

I claim:

The ornamental design for a crochet frame, substantially as shown.
